FLEXIBLE ARTIFICIAL LEECH FISH LURE

James W. Fladebo, Isle, Minn., assignor to Mille Lacs Manufacturing Company, Isle, Minn.

Filed Nov. 21, 1973, Ser. No. 417,977

Term of patent 14 years

Int. Cl. D22—05

U.S. Cl. D22—27

FIG. 1

FIG. 2

FIG. 3

FIG. 4

FIG. 5

FIG. 1 is a view in perspective of a flexible artificial leech fish lure as seen from the front, top and one side showing my new design;

FIG. 2 is a view in perspective thereof as seen from the front bottom and side opposite that shown in FIG. 1;

FIG. 3 is a view in top plan thereof;

FIG. 4 is a view in side elevation thereof; and

FIG. 5 is an enlarged transverse sectional view thereof as seen generally from the line 5—5 of FIG. 4.

I claim:

The ornamental design for a flexible artificial leech fish lure, substantially as shown.
